UNITED STATES PATENT OFFICE.

EDWIN PLACE, OF SCHENECTADY, NEW YORK.

TACHOMETER.

SPECIFICATION forming part of Letters Patent No. 687,650, dated November 26, 1901.

Application filed December 31, 1900. Serial No. 41,624. (No model.)

To all whom it may concern:

Be it known that I, EDWIN PLACE, a citizen of the United States, residing at Schenectady, county of Schenectady, and State of New York, have invented certain new and useful Improvements in Tachometers, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures.

Figure 1 of the drawings is a view in front elevation, partly in section, of my improved tachometer. Fig. 2 is a view of the same, partly in central vertical section, on the broken line 2 2 in Fig. 1, and partly in elevation. Fig. 3 is a view in front elevation of the cylindrical gear-case. Fig. 4 is a view 25 of the gear-rack and spindle broken away at both ends. Fig. 5 is a horizontal section of the gear-case on the broken line 5 5 in Fig. 3. Fig. 6 is a view in side elevation of the same. Fig. 7 is a view in front elevation of 30 a broken-away portion of the tubular inclosure for the gear-rack, showing the gear-case in front elevation. Fig. 8 is a detail view, partly in section, showing the stepped bearing for the inner end of the shaft for operating the centrifugal mechanism and connections between said shaft, centrifugal mechanism, and spindle operated thereby. Fig. 35 9 is a view of the same, partly in vertical cross-section, on the broken line 9 9 in Fig. 8. Fig. 10 is a view in horizontal cross-section, taken on the broken line 10 10 in Fig. 8, showing a top plan view of the slotted portion of the spring-plate. Fig. 11 is a top plan view of the slotted portion of the spring-plate.

My invention relates to the class of instruments known as "tachometers" and employed for measuring the speed of rotating objects.

The object of my invention is to improve the construction and increase the accuracy of such instruments.

Referring to the drawings, the case of the instrument comprises two parts 1 and 2, one containing a chamber for the centrifugal mechanism and the other a chamber for the gear mechanism, which operates the index. The shaft 3 extends axially through the chamber formed by the inclosure 1, being provided with bearing-supports in the end walls 55 of the inclosure adapted to permit a rotative movement of said shaft, and the bearing-support for the inner end of said shaft being in the form of a stepped bearing, as shown at 4, adapted to resist an inward thrust of said 60 shaft. The outer end of said shaft projects through the end wall of the inclosure and is provided with an outer shaft member 5, capable of endwise movement thereupon, the coil-spring 6 being interposed between said shaft 70 members, as shown in Fig. 1. The outer member 5 is provided with an angularly-pointed outer end 7, adapted to fit a similarly-formed recess in a rotating object, as in the end of a shaft, (not shown,) in the usual manner to cause the rotary movements of said object to be transmitted to the tachometer-shaft. By interposing the spring 6 between the shaft members I am able to force the pointed end 75 of the outer member against the rotating object with considerable force without subjecting the stepped bearing at the inner end of the tachometer-shaft to undue friction and wear, such as to interfere with the uniformity of its operation and the accuracy of the 80 instrument. The inclosure 1 also contains the centrifugal mechanism, which comprises the spring-plate 8, having its ends secured at 9 to a boss 10, fixed upon the shaft 3, and its middle portion bowed and provided with 85 a slot 11, adapted to receive and fit and move upon the inner flattened portion 12 of the shaft 3. The arms of the bowed spring-plate may be provided with weights 13 in any known form. Rotary movements imparted to the 90 shaft 3 will thus cause revoluble movements of said weights, and centrifugal force will cause the outward movement of said weights and a flattening movement of said bowed spring varying in accordance with the speed 95 of the moving parts.

The centrifugal mechanism may be caused to operate an index in any known manner. I have shown a spindle 14, extending axially

through a tubular inclosure 15, located within the inclosure 2, the lower end of said spindle projecting through a central aperture 16, formed in the step bearing-block 17, secured 5 upon the upper end of the flattened portion of the shaft 3, which is preferably bifurcated, as shown, the bifurcate ends being secured in recesses in the bearing-block 17 by means of pins or rivets 18. The bearing-block 17 10 forms practically the end of the shaft 3, and the shaft is thus provided with an axial end aperture 16, and the transverse slot 19 between the bifurcate arms intersecting said axial aperture. The end of the spindle 14 15 which projects down through the central aperture 16 is provided with a transverse aperture 20, through which a wire link 21 is passed and extended out through the transverse slot 19, having its ends introverted to embrace 20 the side edges of the spring-plate, as shown in Fig. 9, thus connecting said plate and spindle without weakening the spring or interfering with the movement of either part. The spindle-shaft 3 and centrifugal mechanism 25 are thus connected to rotate in unison, while the movements of the bowed portion of the spring due to variations in centrifugal force will cause reciprocating movements of the connected spindle 14, which may be caused 30 to operate an index in any known manner.

The spindle 14 is preferably provided with an annular toothed gear-rack 31, adapted to operate the index by suitable gear connections. As a means for supporting such mechanism I provide a cylindrical gear-case 21, 35 adapted to be inserted transversely through apertures in the cylindrical inclosure 15 and frictionally held therein. This gear-case is preferably provided with oppositely-located slots 22, which permit the cylinder to be compressed or contracted while being inserted in apertures in the inclosure 15, slightly smaller than the diameter of the gear-case, the resili- 40 ent expansive force of the case-wall being sufficient to securely hold it in place. Said 45 slots 22 are located diametrically opposite each other and permit the spindle 14 to pass diametrically through the gear-case. Portions of the gear-case wall are cut and bent 50 inwardly to form bearing-supports 23 and 24 for the inner ends of the axially-arranged index-shaft 25 and pinion-shaft 26, parallel with the axis of said case and eccentric thereto. Outer bearing-supports for said 55 shafts 25 and 26 are formed in the I-plate 27, which extends transversely of the front end of the case and is frictionally held in slots 28, formed in the front end of the case-wall. The pinion 29 is fixed upon the shaft 26 in 60 position to mesh with a pinion 30, fixed upon the index-shaft, and also to be engaged by a gear-rack 31, comprising a series of annular teeth on that portion of the spindle 14 which passes through the gear-case. The recipro- 65 cating movements of the spindle induced by its connection with the centrifugal mechanism will thus cause operation of the index 33,

fixed upon the shaft 25 and adapted to rotate in proximity to a dial 34, fixed upon the inclosure 2 and covered, if desired, by a glass 35. 70

By having the gear-rack 31 extend diametrically through the gear-case and the pinion 29 supported eccentrically in said case I am able by a slight rotary adjusting movement of the frictionally-held case to force the pinion 29 into more or less close mesh with the gear-rack to take up lost motion and compensate for wear, and this without disturbing the axial position of the index-shaft. To permit of such rotary adjusting movement of 80 the gear-case, the slots 22 are made of a width somewhat greater than the diameter of the gear-rack.

If desired, the spindle 14 may be provided with a piston 36, located in a cylindrical chamber 37, formed in the tubular inclosure 15 by the diaphragms 38, thereby forming a dash-pot construction, which serves as a brake to prevent a too-sudden movement of the operating parts. 85

What I claim as new, and desire to secure by Letters Patent, is— 90

1. In a tachometer, or the like, the combination with a shaft having a flattened portion; and means for rotatively supporting 95 said shaft in operative connection with a rotating object; of centrifugal mechanism connected with said shaft and comprising in part a spring-plate having its middle portion bowed and provided with a slot adapted to 100 receive and fit the flattened portion of said shaft and move thereon as the rotary speed of said shaft varies; and an indicator connected with said centrifugal mechanism.

2. In a tachometer, or the like, the combination with a shaft rotatively supported by bearings at or near its opposite ends and having in one end an axial aperture and near said end a transverse slot intersecting such axial aperture; and means for supporting 110 said shaft in operative connection with a rotating object; of centrifugal mechanism connected with said shaft; an indicator; a spindle operatively connected with said indicator and having its end located within the apertured end of said shaft; and mechanism extending through the transverse slot in said shaft and connecting said spindle with said centrifugal mechanism. 115

3. In a tachometer, or the like, the combination with a shaft having a flattened portion, an axial aperture in one end and a transverse slot in its flattened portion intersecting said axial aperture; means for rotatively supporting said shaft in operative connection with a 120 rotating object; and centrifugal mechanism connected with said shaft comprising in part a spring-plate having its middle portion bowed and provided with a slot adapted to receive and fit the flattened portion of said shaft and move thereon as the rotary speed of said shaft varies; an indicator; a spindle operatively connected with said indicator and having a 125 transversely-apertured end located within 130

the apertured end of said shaft; and a link passed through the transverse aperture in said spindle and slot in said shaft with its ends embracing the side edges of said spring-plate, substantially as described.

4. In a tachometer, or the like, the combination with a shaft having an axial end aperture; means for rotatively supporting said shaft in operative connection with a rotating object; and centrifugal mechanism connected with said shaft; of an endwise-movable spindle having one end supported and reciprocatory in said apertured end of said shaft; said shaft and spindle being connected to rotate in unison; means for rotatively supporting the other end of said spindle; an indicator; and operative connections between said spindle and said indicator and centrifugal mechanism respectively, substantially as described.

5. In a tachometer, or the like, the combination with a shaft having an axial end aperture; means for rotatively supporting said shaft in operative connection with a rotating object; and centrifugal mechanism connected with said shaft; of a rotary and endwise-movable spindle provided with an annular toothed gear-rack and having one end rotatively reciprocatory in the apertured end of said shaft and connected to rotate therewith; means for rotatively supporting the other end of said spindle; an indicator; gear connections between said indicator and gear-rack; and operative connections between said spindle and centrifugal mechanism, substantially as described.

6. In a tachometer, or the like, the combination with centrifugal mechanism; means for supporting the same in connection with a rotating object; and a gear-rack in operative connection with said centrifugal mechanism;

of a tubular inclosure and support for said gear-rack; a tubular gear-case inserted transversely through apertures in said tubular inclosure and frictionally held therein; an index-shaft and gear connections between said shaft and gear-rack supported by said gear-case; and an index, substantially as described. 45

7. In a tachometer, or the like, the combination with an index-operating gear-rack; and a cylindrical inclosure therefor; of a slotted cylindrical gear-case inserted transversely through apertures in said cylindrical inclosure and frictionally held therein with said 50 rack extending diametrically through its slotted portion; a pinion meshing with said gear-rack, and rotatively supported in said gear-case with its axis parallel with the axis of said case and eccentric thereto; an index; an 55 index-supporting shaft axial to said case; and a pinion on said index-shaft meshing with said eccentric pinion, substantially as described.

8. In a tachometer, or the like, the combination with a rotary shaft adapted to connect with a rotating object; a supporting-case; and centrifugal mechanism connected with said shaft; of a spindle reciprocatory in suitable bearings and connected with said centrifugal 60 mechanism to be reciprocated thereby; an index; connections between said index and reciprocatory spindle; a dash-pot cylinder enclosing said spindle and a piston on said spindle located within said cylinder, substantially 65 as described.

In testimony whereof I have hereunto set my hand this 22d day of December, 1900.

EDWIN PLACE.
